UNITED STATES PATENT OFFICE.

WILLIAM JOHN McCARTHY, OF OTTAWA, ONTARIO, CANADA.

LOOSE-LEAF BINDER.

1,333,124.

Specification of Letters Patent. Patented Mar. 9, 1920.

Application filed March 22, 1919. Serial No. 284,235.

To all whom it may concern:

Be it known that I, WILLIAM JOHN McCARTHY, a subject of the King of Great Britain, and resident of the city of Ottawa, 5 in the Province of Ontario, Dominion of Canada, have invented certain new and useful Improvements in Loose-Leaf Binders, of which the following is a specification.

This invention relates to improvements in 10 loose leaf binders, and the objects of the invention are to provide a simple and effective form of binder in which the binding members may be readily released from binding, but may be kept locked in position.

15 Further objects are to provide a uniform movement between the two binding members during the opening of the binder, and generally to improve and simplify the construction of the device and enable the various parts to better perform the functions required of them. It consists essentially of the improved construction hereinafter described in detail in the accompanying specification and drawings.

25 In the drawings:

Figure 1 is a perspective view of the binder.

Fig. 2 is a front elevation of the binding elements closed.

30 Fig. 3 is a perspective view of the operating plate.

Fig. 4 is a front elevation of the binding elements open.

Fig. 5 is a cross sectional view.

35 Fig. 6 is a perspective view of one of the binding members.

Fig. 7 is a cross sectional view on the line X—X of Fig. 5.

In the drawings like characters of reference indicate corresponding parts in all the figures.

Referring to the drawings, A and B represent the two binding elements movable to and from each other and usually forming 45 part of a loose leaf book, the covers of which book will be attached to the elements A and B, the said covers not being, however, shown in the drawings. C represents the back plate forming the back of the 50 book and also constituting a support for certain of the working parts as hereinafter described.

Each of the binding elements A and B are formed with a plurality of projecting arms 55 10 which carry studs 11 which extend through inclined slots 12 in the controlling

or operating plate D, which plate is provided with a series of slots 12, oppositely inclined and arranged in staggered rows, the studs 11 being formed with their heads projecting over the edge of the slots whereby when the plate D is moved longitudinally the inclined slots, communicating motion through the studs 11 will cause the binding members to be moved outwardly or inwardly, 60 or conversely when the binding members are moved inwardly or outwardly the plate D will be moved longitudinally.

Means are provided for locking the plate D in any longitudinal position, and means 70 are shown for this comprising a spring dog 14 mounted on a bracket 15 at one end of the plate D and adapted to engage a ratchet 16 formed on one side of a rod 17 extending longitudinally on the back plate C and supported thereon, with freedom to turn half a revolution at least, the rod as illustrated being supported from suitable brackets 18 and 19 and also receiving some support from a depending lug 20 on the plate D. 75 The turning movements of the rod 17 is limited by means of projecting pins 21 on one end of the same designed, when the rod has been turned one-quarter of a revolution, to engage against the back plate C. 80

It will be seen that movement of the binding members will be prevented so long as the dog 14 is not released from the ratchet 16 and it is necessary that the rod 17 should be turned before this release takes place, and I 90 preferably provide a suitable form of swivel lock E at the end of the rod and connected therewith in such a way that when the barrel of the lock is turned by the insertion of the key the rod 17 will also be turned to release 95 the ratchet 16 and permit the binding members to open.

Means are provided for causing the binding members to open automatically when they are released. The means I have provided for this purpose comprise a plurality of telescoping binding posts 22 formed with two parts 23 and 24 separated by a strong spiral compression spring 25 mounted within the parts. The rod 17 is 100 held in normally engaged position by means of a spiral spring 26 having one end bearing against the plate C and the other end connected to the rod. Opening of the binding members is also assisted by means of a 110 spring 27 mounted on the rod 17 and bearing at one end against the lug 20 whereby

the spring will normally exert a pressure against the lug which is communicated by the plate D to the binding bars which will tend to open the same.

5 In addition to the usual binding posts 22 I provide a central removable binding post 30 formed in two telescopic sections 31 and 32 normally separated by an internal spiral spring 33, the ends of which post are adapted to seat in sockets 34 and 35 in the binding member whereby the binding post 30 may be readily removed on telescoping the parts 10 31 and 32 together and disengaging the ends from the sockets, this operation being frequently desirable in a binder of this type where certain of the binding posts will be engaged with open slots of the loose leaves of the binder, while other binding posts will be engaged with closed perforations. If, 15 20 for instance, the binding post 30 were engaged with a closed perforation while the remaining binding posts were engaged with open slots, it will be seen that the loose leaves might be readily removed as soon as 25 the binding post 30 was removed.

In operation it will be seen that whenever the lock E is turned the rod 17 will be turned to release the ratchet and permit the binding members to spring apart by the 30 spring action already described, both the binding bars being caused to move in unison by the arrangement of the inclined slots 12. When it is desired to close the binder the binding bars are simply forced toward each 35 other, the spring dog 17 running over the

ratchet 16 to permit the closing of the binder but not the opening thereof, and the binder cannot be opened until it is unlocked.

As many changes could be made in the above construction, and many apparently 40 widely different embodiments of my invention, within the scope of the claim, constructed without departing from the spirit or scope thereof, it is intended that all matter contained in the accompanying specification and drawings, shall be interpreted as 45 illustrative and not in a limiting sense.

What I claim as my invention is:

In a binder, and in combination, two binding elements, a back plate, a rod extending longitudinally on the back plate having freedom to turn a part of a revolution, a controlling plate movable longitudinally with respect to the rod and being operatively connected to the binding members in such a 55 way that when the plate is moved longitudinally the binding members will be moved in or out, means on the plate engaging the rod to prevent movement of the plate in one direction and a coiled compression spring 60 encircling the rod and bearing against the plate to move the latter in such direction upon the release of said last mentioned means.

In witness whereof I have hereunto set 65 my hand in the presence of a witness.

WILLIAM JOHN McCARTHY.

Witness:

RUSSEL S. SMART.
